United States Patent Office

Des. 223,876
Patented June 13, 1972

223,876

HAND MASSAGER

Ronald O. Hilger, Elmhurst, Ill., assignor to Associated Mills, Inc.

Filed Dec. 10, 1970, Ser. No. 26,391

Term of patent 14 years

Int. Cl. D24—02

U.S. Cl. D83—1

Fig. 1

Fig. 2

Fig. 3

Fig. 4

FIG. 1 is a perspective view of the hand massager showing my new design;

FIG. 2 is a side elevation thereof;

FIG. 3 is an end elevation thereof; and

FIG. 4 is a top plan view thereof.

I claim:

The ornamental design for a hand massager, as shown.
